UNITED STATES PATENT OFFICE

108,256

DESIGN FOR A CONFECTIONERY PRODUCT

Petro Ariolo, Chicago, Ill.

Application December 3, 1937, Serial No. 73,333

Term of patent 7 years

To all whom it may concern:

Be it known that I, Petro Ariolo, a citizen of the United States, residing at Chicago, in the county of Cook and State of Illinois, have invented a new, original, and ornamental Design for Confectionery Products, of which the following is a specification, reference being had to the accompanying drawing, forming part thereof.

In the drawing, Fig. 1 is a perspective view and Fig. 2 is a horizontal section taken substantially on the line 2—2 of Fig. 1, of a confectionery product, showing my new design.

I claim:

The ornamental design for a confectionery product, as shown.

PETRO ARIOLO.
